RAILWAY SIGNALING APPARATUS

Paul H. Crago, Wilkinsburg, Pa., assignor to The Union Switch & Signal Company, Swissvale, Pa., a corporation of Pennsylvania

Application November 15, 1938, Serial No. 240,525

5 Claims. (Cl. 246—130)

5 My invention relates to railway signaling apparatus, and has for an object the provision of novel and improved means for transferring the operation of a signal from its normal source of current to a stand-by source in the event that the voltage of the normal source drops below the operating voltage of such signal.

10 I shall describe one form of apparatus embodying my invention, and shall then point out the novel features thereof in claims.

15 The accompanying drawing is a diagrammatic view showing a preferred form of apparatus embodying my invention when applied to the control of a highway crossing signal.

20 Referring to the drawing, the reference characters 1 and 1a designate the traffic rails of a stretch of railway track X over which traffic moves in both directions, and which is intersected at grade by a highway H. A highway crossing signal S is located at the intersection. Signal S may be any one of the several forms of highway crossing signals, and is illustrated in the drawing by a symbol employed in the art to represent a signal of the type having an oscillating signal arm.

25 Signal S is arranged to be controlled by traffic operating over the stretch of railway track. As herein shown, rails 1 and 1a are divided by means of the usual insulated rail joints 2 into track sections D—E and E—F, extending in opposite directions from the intersection. The track sections D—E and E—F are provided with track circuits, each circuit comprising a suitable source of current, such as track battery 3, connected across the track rails at one end of the section, and one winding of an interlocking relay XR connected across the rails at the other end, winding W1 being interposed in the circuit for section D—E and winding W2 being interposed in the circuit for section E—F. Winding W1 is provided with back contact 4, closed only in the released position of the armature associated with winding W1, and with front "flagman" contacts 5 and 6, closed in the locked position as well as the energized position of the armature. Similarly, winding W2 is provided with back contact 7 and front "flagman" contacts 8 and 9.

50 Signal S, as shown, is provided with an operating mechanism designated as a whole by the reference character M. The operating mechanism of signal S may take different forms and, as here shown, is of the type described and covered by United States Letters Patent No. 1,498, 55 157, granted on June 17, 1924 to C. W. Dunham

5 for Highway crossing signal. As herein shown, the signal mechanism comprises in its essential elements a signal arm 10 carrying a shield 10a and a lamp L, and pivotally pinned for rotation about a pin 11 secured to a mounting member (not shown). The arm 10 is connected by means of a member 12 with a pivotally arranged armature 13. The armature 13 is adapted to be attracted alternately to one magnet 14 or the other magnet 15 of a normally deenergized operating element, and is arranged to close contact 16—17 when attracted to magnet 14, and to close contact 17—18 when attracted to magnet 15. The armature 13 and arm 10 are normally latched to the position shown by means of a normally energized latching means herein shown as an electromagnet 19 adapted to attract an armature 20, which is pivotally mounted on a pin 21. The armature 20 is provided on its extreme outer end with a projecting pawl 22, which is adapted to coact with the lower end of armature 13. When magnet 19 is energized, armature 20 is attracted to a position wherein pawl 22 lies in the path of movement of armature 13 with the result that armature 13 and arm 10 are latched in the position shown in the drawing. In the latched position of the arm 10, the arm and the shield 10a carried thereby are adapted, in accordance with the usual practice, to be obscured behind obstructing plates (not shown). When the magnet 19 is deenergized, armature 20 is released and swings in a clockwise direction to release armature 13 from its latched position. The armature 20 of the latching means also controls a circuit controller comprising two contact members 23 and 24, which are biased into mutual engagement. Control of the contact 23—24 is established by providing armature 20 with a slot 21a through which passes the mounting pin 21, so that armature 20 is capable of longitudinal as well as swinging movement. The armature 20 carries a knob 22a of insulating material which is adapted at times to engage contact 24 to open the contact 23—24.

45 The operation of the signal is as follows: Normally, when magnet 19 is energized, armature 13 is engaged by pawl 22 of armature 20, so that armature 13 is retained in its latched position, and armature 20 is operated to its extreme right-hand position, as shown in the drawing, so that contact 23—24 is open. When, however, magnet 19 is deenergized and permits armature 20 to swing in a clockwise direction, armature 13 is unlatched, and contact 23—24 is closed by virtue of its bias to complete the con- 50 55

trol circuit for magnet 15 of the operating means. The unlatching of armature 13 permits the arm 10 to swing downwardly, and the energization of magnet 15 attracts armature 13 to swing arm 10 upwardly to the right, as viewed in the drawing. The swinging of armature 13 to the right opens contact 16-17 interposed in the control circuit for magnet 15, and closes contact 17-18 interposed in the control circuit for magnet 14. The deenergization of magnet 15 permits armature 13 and arm 10 to swing downwardly, and the energization of magnet 14 attracts the armature and arm to the left, the movement of the armature 13 reclosing contact 16-17 and reopening contact 17-18. This cycle of operation is periodically repeated as long as the apparatus is controlled to its operating condition, the parts usually being so proportioned that an operating cycle is completed substantially every two seconds or thirty times per minute, and usually being further proportioned so that a predetermined operating voltage is necessary to effect proper operation, and latching up after operation, of signal S. Then, when magnet 19 is reenergized, armature 20 is attracted to its position wherein armature 13 is engaged by pawl 22 and is held at its latched position, and the armature 20 is shifted to its extreme right-hand position by virtue of the weight of the armature 13 and arm 10 to open contact 23-24 and thereby terminate the operation of signal S.

The reference character T designates a transformer provided with secondary windings 25 and 26, and with a primary winding 27 connected with a suitable source of alternating current, such as a generator not shown.

The reference character 28 designates a full wave rectifier having its input terminals 29 and 30 constantly connected across the terminals of secondary winding 25 of transformer T, and provided with output terminals 31 and 32.

The reference character B designates a suitable stand-by source of current, herein shown as a battery.

The reference character PTR designates a power transfer relay which serves, as will be explained hereinafter, to transfer the operation of signal S from its normal source of current to the stand-by source of current in the event the voltage of the normal source drops below a predetermined level. The relay PTR is connected across output terminals of rectifier 28 the circuit passing from terminal 31 of rectifier 28 through two branch circuit paths to the operating winding of the relay and to terminal 32 of the rectifier, a first circuit path of which serially includes front "flagman" contact 5 of winding W1 and front "flagman" contact 8 of winding W2, and the second circuit path of which serially includes front contact 33 of relay PTR and a resistor 34. It should be noted that the second path in the circuit for relay PTR includes its own front contact 33 and a resistor 34, and that the first path in the circuit for relay PTR includes front "flagman" contacts of windings W1 and W2, but excludes the front contact 33 and resistor 34. It is apparent, therefore, that relay PTR may be energized and picked up only over its first circuit path, but that when once picked up it may be held up over its second circuit path wherein the resistor 34 decreases the energy level of the relay.

The operating element of mechanism M for signal S is provided with an energizing circuit usually passing from output terminal 31 of its

normal source of current, rectifier 28, through front contact 33 of relay PTR, magnet 14 or 15 of the mechanism M in multiple with the winding of a bell 35 of the mechanism, contact 24-23, and front contact 36 of relay PTR to the other terminal 32 of the rectifier. Whenever relay PTR is released, however, the operating element of signal S is connected across the stand-by source, the circuit in that event passing from one terminal of battery B through back contact 37 of relay PTR, magnet 14 or 15 of the mechanism M in multiple with the winding of bell 35, contact 24-23, and back contact 38 of relay PTR to the other terminal of battery B. The lamp L provided for signal arm 10 is usually connected across the secondary winding 26 of transformer T over a circuit passing from one terminal of winding 26 through front contact 39 of relay PTR, back contact 4 of winding W1 or back contact 7 of winding W2, the filament of lamp L, and front contact 40 of relay PTR to the other terminal of secondary winding 26 of transformer T. Whenever relay PTR is released, however, the lamp L is connected across the stand-by source of current, battery B, the circuit passing from one terminal of battery B through back contact 41 of relay PTR, back contact 4 of winding W1 or back contact 7 of winding W2, the filament of lamp L, and back contact 42 of relay PTR to the other terminal of battery B. 80

The latching magnet 19 of signal mechanism M is normally energized over a circuit passing from one terminal of battery B through front "flagman" contact 6 of winding W1, front "flagman" contact 9 of winding W2, and the operating winding of magnet 19 to the other terminal of battery B. 85

Normally, the apparatus is in the condition illustrated in the drawing. In this condition of the apparatus, no train is operating upon section D-E or E-F so that windings W1 and W2 of relay XR are energized, relay PTR is connected across the output terminals of rectifier 28 over both its first and second circuit paths, the latching element for mechanism M is energized, and the operating element for mechanism M is deenergized. 40 45

In the event that a train enters section D-E or E-F in approaching the intersection, the winding W1 or W2 associated with the track section so entered is released. In explaining the operation of the apparatus embodying my invention, I shall assume that section D-E is entered by an eastbound train approaching the intersection with the result that winding W1 releases to close back contact 4 and to open front "flagman" contacts 5 and 6. The opening of front contact 5 opens the first branch path provided in the circuit for relay PTR, the relay being retained energized over its second branch path, and the opening of front contact 6 of winding W1 opens the circuit for latching magnet 19 of mechanism M, thereby releasing its armature 20 and closing contact 23-24 to establish the operating condition for signal S, which now operates from rectifier power in the manner described hereinbefore. The closing of back contact 4 of winding W1 completes the circuit for lamp L of the signal arm, whereby the lamp displays a lighted indication to highway users. 55 60 65 70

In the event that the voltage of the normal source of supply for mechanism M remains above the value necessary to effect proper operation and proper latching of the signal at the termination of its operation, relay PTR remains ener- 75

gized and signal S continues to operate from the rectifier power until such time as the train vacates section D—E and winding W1 picks up.

The values of resistor 34 and the winding of relay PTR are so proportioned, however, that in the event the power output of rectifier 28 falls below the value necessary to properly operate and latch signal S, relay PTR will release. When this happens, the operating element of the mechanism for signal S and the lamp L provided for the signal arm of signal S are transferred to the battery stand-by power over circuits previously traced. The operating element of signal S and lamp L continue to operate from the battery power until such time as the train vacates section D—E and winding W1 picks up. When winding W1 picks up, the operation of signal S and lamp L is terminated, the signal arm being latched to its obscured position, and the first circuit for relay PTR is completed, whereby if rectifier 28 is energized, relay PTR picks up to restore the apparatus to its normal condition.

It should be noted that lamp L for the signal arm 10, being connected across secondary winding 26 of transformer T, is normally independent of the operation of rectifier 28. Similarly, the latching magnet 19 is connected across the stand-by source B, whereby the current supplied to such magnet is not interrupted in the event that the power output of rectifier 28 varies so that relay PTR releases or picks up. It should further be noted that relay PTR is so controlled that, when signal S is controlled to its operating condition and relay PTR once becomes released due to a low voltage output of rectifier 28, the relay is not picked up to transfer the operation of signal S to rectifier power until the operation of the signal is terminated and the signal is latched up when the train clears the intersection. It can be seen, therefore, in the event that the output voltage of rectifier 28 is critical, a pumping action, that is, alternate picking up and releasing of the relay armature does not result once the relay PTR is released.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track provided with a track circuit including a track relay, a signal which requires a given operating voltage for operation, a first source of current, a power transfer relay normally energized from said first source of current over a pick-up circuit controlled by said track relay and effective when said track relay is picked up to establish a given energy level in said power transfer relay effective to pick up its armature, a stick circuit for energizing said power transfer relay from said first source of current including a front contact of said power transfer relay and a resistor whereby when said track relay is released there will be established in said power transfer relay an energy level effective to maintain its armature picked up provided the voltage applied to its windings exceeds the operating voltage of said signal, circuit means controlled by said track relay and said power transfer relay for energizing said signal from said first source of current when and only when said track relay is released and said power transfer relay is picked up, a second source of

current, and other circuit means controlled by said track relay and by said power transfer relay for energizing said signal from said second source of current when and only when said track relay is released and said power transfer relay also is released.

2. In combination, a stretch of railway track intersected by a highway and divided into a track section provided with a track circuit including a track relay, a highway crossing signal 10 located at such intersection comprising an operating element which requires a given operating voltage for operation and a signal lamp, a source of alternating current, a rectifier for rectifying said alternating current, a power transfer relay 15 normally energized over a pick-up circuit controlled by said track relay and receiving energy from the output terminals of said rectifier, stick circuit means for said power transfer relay receiving energy from the output terminals of said rectifier and including a resistor whereby when said track relay is released said power transfer will be held energized if and only if the voltage received by the relay from said rectifier exceeds the operating voltage of said signal, means controlled by said track relay and by said power transfer relay and effective when said track relay is released and said power transfer relay is picked up for energizing said signal lamp from said source of alternating current, other means controlled by said track relay and by said power transfer relay and effective when said track relay is released and said power transfer relay is picked up for energizing said operating element from said rectifier, a second source of current, and means controlled by said track relay and by said power transfer relay and effective when said track relay and said power transfer relay are both released for energizing said signal lamp and said operating element from said second source of current.

3. In combination, a stretch of railway track intersected by a highway and a track section having a track relay, a highway crossing signal located at such intersection comprising a normally deenergized operating element which requires a given operating voltage for operation and a normally energized latching element, a first source of current, a power transfer relay normally energized from said first source of current over a pick-up circuit controlled by said track relay, a stick circuit for energizing said power transfer relay from said first source of current and including a resistor whereby when said track relay is released the armature of said power transfer relay is maintained in its picked up condition only when the voltage applied to its winding is equal to or exceeds the operating voltage of the operating element of said signal, circuit means controlled by said track relay and by said power transfer relay and effective when said track relay is released and said power transfer relay is picked up for energizing the operating element of said signal from said first source of current, a second source of current, circuit means controlled by said track relay for normally energizing the latching element of said signal from said second source of current, and circuit means controlled jointly by said track relay and by said power transfer relay and effective when said track relay and said power transfer relay are both released for energizing the operating element of said signal from said second source of current.

4. In combination with a section of railway track having a track relay responsive to traffic 75

- conditions in the section, a signal which requires a given operating voltage for operation, two sources of current one of which is a normal source and the other of which is a stand-by source, a 5 normally energized power transfer relay, a pick-up circuit for said power transfer relay receiving energy from said normal source and controlled by said track relay, a stick circuit for said power transfer relay also receiving energy from said 10 normal source and including a resistor whereby when said signal is caused to operate said power transfer relay is maintained picked up only if the voltage received by the relay from the normal source exceeds the operating voltage of said signal, and means controlled by said power transfer 15 relay for conditioning said signal for operation from one or the other of said two sources of current.
5. The combination with a section of railway 20 track having a track relay responsive to traffic conditions in the section for controlling the oper-

ation of a signal which requires a given operating voltage for operation, the signal usually being operated from a normal source of current but being operated from a stand-by source of current in the event of a failure of power from the normal source, of a normally energized power transfer relay, a pick-up circuit for said power transfer relay controlled by the track relay and receiving energy from the normal source of current, a stick circuit for said power transfer relay 10 also receiving energy from the normal source of current and including a resistor whereby when the signal is operating said power transfer relay is maintained picked up only if the voltage received by the relay from the normal source exceeds the operating voltage of the signal, and means controlled by said power transfer relay for 15 conditioning the signal for operation from the normal or from the stand-by source of current.

PAUL H. CRAGO. 20

CERTIFICATE OF CORRECTION.

Patent No. 2,186,800.

January 9, 1910.

PAUL H. CRAGO.

It is hereby certified that error appears in the printed specification of the above numbered patent requiring correction as follows: Page 3, second column, line 43, claim 3, after the word "and" insert provided with; and that the said Letters Patent should be read with this correction therein that the same may conform to the record of the case in the Patent Office.

Signed and sealed this 5th day of March, A. D. 1910.

Henry Van Arsdale,

(Seal)

Acting Commissioner of Patents.
